CLAIM

We claim the ornamental design for a handle for a power tool, as shown and described.

DESCRIPTION

FIG. 1 is a perspective view of a handle embodying the present invention and shown supported on a power tool; FIG. 2 is a left side view of the handle shown in FIG. 1; FIG. 3 is a top view of the handle shown in FIG. 1; FIG. 4 is a right side view of the handle shown in FIG. 1; and,

FIG. 5 is a front view of the handle shown in FIG. 1.

The broken line showing of the power tool in the drawings is for illustrative purposes only and forms no part of the claimed design. In addition, the bottom and rear of the handle for a power tool are not visible in normal intended use and form no part of the claimed design.
